MACERATOR AND JUICE EXTRACTOR

Rolland E. Klug, Glen Ellyn, Ill.

Application November 2, 1949, Serial No. 5,831

Term of patent 14 years

(Cl. D89—1)

To all whom it may concern:

Be it known that I, Rolland E. Klug, a citizen of the United States, residing at Glen Ellyn, county of Du Page and State of Illinois, have invented a new, original, and ornamental Design for a Macerator and Juice Extractor, of which the following is a specification, reference being had to the accompanying drawing, forming a part thereof, in which—

Fig. 1 is a front elevational view of a macerator and juice extractor showing my new design;

Fig. 2 is a top plan view thereof;

Fig. 3 is a side elevational view thereof; and

Fig. 4 is a rear elevational view thereof.

I claim:

The ornamental design for a macerator and juice extractor, as shown.

ROLLAND E. KLUG.
